Inventor:
FRED E. KLING,
by
D. Anthony Kaina
his Attorney.

Patented Apr. 28, 1925.

UNITED STATES PATENT OFFICE.

FRED E. KLING, OF YOUNGSTOWN, OHIO.

LADLE.

Application filed October 4, 1923. Serial No. 666,454.

To all whom it may concern:

Be it known that I, FRED E. KLING, a citizen of the United States, and resident of Youngstown, in the county of Mahoning and State of Ohio, have invented certain new and useful Improvements in Ladles, of which the following is a specification.

This invention relates to ladle cars, and more particularly to hot metal ladle cars used to transport molten metal around foundries, blast furnaces and the like.

One object of this invention is to provide a ladle of the class described, the shape of which is as close to a sphere as is practical to make, and, therefore, the radiating surface is reduced to a minimum.

Another object is to provide a car having the top or upper section of the ladle so shaped that the opening through which the metal is poured will be reduced to a minimum, and the sides of said section will overlie the molten metal, thereby reducing the area of molten metal exposed directly to the atmosphere, thus lessening the cooling of the metal and also reducing the possibility of the metal splashing from the car.

Another object is to provide a car having the ladle so shaped that the center of gravity is considerably lower than that of the customary inverted frustum of a cone type ladle, and is, therefore, less liable to turn over on a defective track, or in case the car should be derailed.

A further object is to provide a hot metal ladle car having the novel construction, design and combination of parts hereinafter described, and illustrated in the accompanying drawings.

In the drawings, Figure 1 is a top plan of a car constructed in accordance with my invention.

Figure 2 is a side elevation, the right hand half of which is sectioned along the longitudinal center line of the car.

Figure 3 is an end elevation of the car.

Figure 4 is a transverse sectional elevation on the line IV—IV of Figure 2.

Referring more particularly to the drawings, the numerals 2 and 3 designate the trucks of the car, which may be of any suitable construction and which support a body frame 4 having a central depressed portion 5 and ladle supports 6 and 7. Couplers 8 are attached to the frame 4 in the usual manner to provide for the connecting of the car with a locomotive or to other cars.

A ladle of substantially or nearly spherical contour is mounted on the ladle supports 6 and 7. The ladle comprises a substantially hemispherical bottom portion 9, a cylindrical central portion 10, and a frustoconical top portion 11 having an open upper end forming a contracted opening or port 12. The ladle is of the usual construction and comprises a metal shell 14 lined with a layer of suitable refractory material 15.

Trunnion supporting members 16 are secured on diametrically opposite sides of the ladle, and are provided with horizontally spaced trunnions 17 mounted in suitable bearing depressions or seats 18 in the upper faces of the supports 6 and 7. Each of the members 16 also carries a lifting trunnion 19, the axis of which is materially above the horizontal axis of the ladle, and in vertical alignment therewith. The trunnions 19 are adapted to receive the lifting chains from a crane or other overhead supporting device, whereby the ladle may be lifted from the car body for tilting. It will be readily apparent that with the trunnions 19 located above the horizontal axis of the ladle, accidental tilting of the ladle is prevented.

The trunnions 17 are adapted to support and steady the ladle during the travel of the car, and are also used to support the ladle when it is desired to tilt it on the car. The trunnions 17 are so arranged that the ladle may be tilted to either side of the car about the axis of either pair of the aligned trunnions 17 at the opposite sides.

Suitable tilting lugs 21 are secured to the cylindrical portion of the ladle body at diametrically opposite sides of said portion from said trunnions. The lugs 21 are adapted to receive lifting chains or the like and to tilt the ladle about the trunnions 17.

Those skilled in the art to which my invention belongs will readily appreciate the advantages to be gained by a hot metal car constructed in accordance with my invention. The molten metal will have a minimum amount of exposure to the atmosphere, the likelihood of splashing is reduced to a minimum, the center of gravity is lowered, and the novel shape which closely approximates a sphere reduces the radiating surface of the ladle to a minimum.

While I have shown and described only one specific embodiment of my invention, it will be understood that I do not wish

to be limited to the specific details thereof, since various modifications may be made without departing from the scope of my invention as defined in the appended claims.

5 I claim:

1. A ladle for hot metal cars having an approximately hemispherical bottom portion, a cylindrical central portion, and a frusto-conical top or nose portion having 10 its upper end open to form a contracted opening.
2. A hot metal car comprising a suitably supported body and a ladle carried by said body, and having an approximately hemispherical bottom portion, a cylindrical central portion, and a contracted open top or nose portion.
3. A hot metal car comprising a suitably supported body and a ladle carried by said 20 body, and having an approximately hemispherical bottom portion, a cylindrical central portion, and a contracted open top or nose portion, supporting members arranged on opposite sides of said cylindrical portion, each of said supporting members being provided with a pair of horizontally 25 spaced trunnions, and a lifting trunnion, the axis of which is in the vertical plane of the horizontal axis of the ladle and substantially 30 above the same.
4. A hot metal car comprising a suitably supported body and a ladle carried by said body, and having an approximately hemispherical bottom portion, a cylindrical central portion, and a contracted open top or 35

nose portion, supporting members arranged on opposite sides of said cylindrical portion, each of said supporting members being provided with a pair of horizontally spaced trunnions, rigid upright supports on 40 said car, upon which said trunnions are mounted, a lifting trunnion, the axis of which is in the vertical plane of the horizontal axis of the ladle, and substantially 45 above the same, and attachments for a tilting means on the diametrically opposite sides of said cylindrical portion from said lifting trunnions.

5. A hot metal car comprising a wheeled body portion, a ladle carried by said body 50 and having a substantially hemispherical bottom portion, a cylindrical central portion, and a frusto-conical top or nose portion open at its upper end to form a contracted opening, supporting members arranged on opposite sides of said cylindrical portion, each of said supporting members being provided with a pair of horizontally 55 spaced trunnions, rigid upright supports on said car upon which said trunnions are mounted, a lifting trunnion, the axis of which is in the vertical plane of the horizontal axis of the ladle and substantially 60 above the same, and attachments for tilting means on the diametrically opposite sides of said cylindrical portion from said lifting trunnions.

In testimony whereof, I have hereunto set my hand.

FRED E. KLING.
